(74) Attorney, Agent, or Firm—Harness, Dickey & Pierce P.L.C.

(57) **CLAIM**

The ornamental design for a saw handle, as shown and described.

DESCRIPTION

FIG. 1 is a left side perspective view of a saw handle;

FIG. 2 is a right side perspective view thereof;

FIG. 3 is a left side view thereof;

FIG. 4 is a right side view thereof;

FIG. 5 is a top view thereof;

FIG. 6 is a bottom view thereof;

FIG. 7 is a back view thereof; and,

FIG. 8 is a front view thereof.

The lines shown in phantom in all of the figures are for illustrative purposes only and do not form part of the invention.
